LIFTING JACK

Frank V. Povandra, Denver, Colo.

Application April 22, 1938, Serial No. 203,659

2 Claims. (Cl. 254—95)

My invention relates to lifting jacks and more particularly to that type wherein a plurality of pivoted members are employed for varying the lifting height.

One of the principal objects of my invention is to provide a lifting jack equipped with a plurality of pivoted members operable for varying the height thereof.

Another object of my invention is to provide a jack of the above described character which is simple in construction, durable in use, efficient in operation and economical in manufacture.

Other objects and advantages will be apparent from the following description, appended claims and annexed drawings.

Referring to the drawings wherein like reference characters designate like parts throughout the several views:

Figure 1 is a top plan view of my invention illustrating the support casing in section.

Figure 2 is a rear elevation, several of the parts being removed.

Figure 3 is a sectional view taken on the line 3—3 of Figure 2.

Figure 4 is a sectional view taken on the line 4—4 of Figure 3.

Figures 5, 6 and 7 are detail sectional views taken on the lines 5—5, 6—6 and 7—7 of Figure 4 respectively.

Figures 8 and 9 are detail sectional views taken on the lines 8—8 and 9—9 of Figure 1 respectively.

In practicing my invention I employ a base 5 integrally formed with a hollow support casing 6 having vertically and horizontally extending channels 6a and 6b respectively in which is slidably mounted a plurality of articulated members 7. Said channels are connected together by an inflected section 6c whereby to permit said members to be disposed in aligned position in said channels.

The articulated members 7 are each in the form of a link having a block portion 8 fashioned on an outer face with rack teeth 9 for engagement with gear teeth of a gear 10 fixed to a shaft 11 journaled in a bearing 12 mounted on the casing 6 and a bearing 13 mounted on the base 5.

The links are also fashioned with bifurcated end portions for receiving reduced portions of the adjacent links and through which extend pintles 14 whereby the links are pivotally connected together. The sides of the links are provided with wear plates 15 secured thereto by means of the pintles 14 and said wear plates are fashioned with slots 16 for embracing the ends

of latch actuating members 17. The actuating members 17 extend through the block portions 8 and are fashioned with offset sections 18 operable within transversely extending slots 19 formed in said portions 8. The block portions 8 are also fashioned with longitudinally extending bores 20 having latch bolts 21 slidable therein.

Said latch bolts are provided with apertured heads 22 through which extend the offset sections 18 of the members 17. The latch bolts are adapted to extend beyond the bores 20 and seat within similar bores 23 formed in the reduced portion of the adjacent link whereby to maintain the links in aligned position as hereinafter more fully described.

Formed on the members 17, within the slots 19, are yokes 24 having sliding connections with the ends of coil springs 25, the opposite ends of said springs being connected to the respective reduced portions by means of pins 26 as clearly illustrated in Figures 4 and 7 of the drawings. The outer ends of the members 17 are offset and extend at right angles relative to each other for engagement with projections 27 and 28 formed on the inner walls of the channel 6a.

The projection 27 extends in the path of one of the offset ends of the members 17 and engages the latter to actuate the latch bolt into projected position when the links are moved upwardly within the channel 6a by the action of the gear 10. When the gear 10 is operated in a reverse direction the projection 28 engages the opposite ends of the members 17 when the links are moved downwardly thereby actuating the latch bolt to retracted position. As the links are moved upwardly in the channel 6a, the latch bolts are actuated to extended position to effect latching of the links with each other thereby preventing the links or members 17 from pivoting as they are moved upwardly out of the casing 6.

The base 5 is provided with a pair of bearings 29 in which is journaled a shaft 30 having fixed thereon a gear 31 meshing with a gear 32 fixed on the shaft 11 through the medium of which the gear 10 and members 7 are actuated. Also fixed on the shaft 30 is a bevel gear 33 meshing with a similar gear 34 rotatably mounted on a shaft 35 and having connected thereto for movement therewith a brake drum 36 about which is positioned a brake band 37.

The shaft 35 is rotatably mounted in bearings 38 and has slidably connected thereon a clutch element 39 for engagement with a similar element 40 carried by the gear 34 whereby to connect said gear 34 and said brake drum 36 in op-

erating condition with the shaft 35. A spring 41 is mounted on the shaft 35 and interposed between the clutch element 39 and the adjacent bearing 38 whereby to normally urge the clutch element 39 towards the element 40. An operating arm 42 connects the clutch element 39 to a shift arm 43, said shift arm being fashioned with a plurality of position grooves 44 in which a roller 45 is adapted to selectively seat.

10 The roller 45 is rotatably mounted within a yoke 46 carried on one end of an arm 47 for actuating the brake band 37. The brake band 37 is fashioned with laterally extending spaced ends 48 and 49 connected together by means of a spring 50 for normally maintaining the brake in contracted condition about the drum.

15 The end 49 of the band is secured to a bracket 51 mounted on the base 5. Each of the ends are provided with openings through which the arm 47 extends. The arm 47 is provided with a collar 52 for engaging the under face of the end 48 whereby when the arm 43 is shifted to raise the yoke 46, said collar will engage the end 48 and release the band 37 about the drum 36. Obviously, shifting of the arm 43 serves to effect engagement of the clutch elements and a release of the brake drum. Shifting of the arm in an opposite direction serves to disengage the clutch elements and permit application of the brake.

20 Further, shifting of the arm 43 to move the clutch elements still further apart serves to release the brake without effecting engagement of the clutch elements thereby permitting a lowering of the members 7 within the channel 6a. The shaft 35 is provided with end sections for receiving a crank or other similar tool for operat-

ing the device. However, it is to be understood that any other source of power, other than manual, may be used for operating the shaft 35.

The ends of the arm 43 are slidably mounted in bearings 53 secured to the base 5 whereby the 5 arm 43 is maintained in the bearings 53 against vertical and lateral movement.

What I claim is:

1. A device of the character described, comprising, a base fashioned with a casing formed 10 with a pair of connected channels, a plurality of articulated members movable in said channels, means for moving said members from one to another of said channels, latching devices carried within said members and equipped with 15 elements extending through said members and terminating in angularly disposed ends without said members, and a projection formed on said casing within one of said channels for engagement with said ends whereby to operate said 20 devices for maintaining said members in aligned condition after movement from one channel to another.

2. A device of the character described, comprising, a base fashioned with a casing formed 25 with a pair of connected channels, a plurality of articulated members movable in said channels, means for moving said members from one to another of said channels, latching devices operable for maintaining said members in aligned 30 condition after movement from one channel to another, and a fixed projection on said casing and disposed in one of said channels for engagement with said devices for operating the latter.

FRANK V. POVANDRA.
